UNITED STATES PATENT OFFICE

EMIL BEHRINGER AND HERMAN BEHRINGER, OF BROOKLYN, NEW YORK.

MANUFACTURE OF RADIATOR-TUBES.

1,029,099.

Specification of Letters Patent.

Patented June 11, 1912.

Original application filed April 13, 1910, Serial No. 555,276. Divided and this application filed September 12, 1910. Serial No. 581,598.

To all whom it may concern:

Be it known that we, EMIL BEHRINGER and HERMAN BEHRINGER, citizens of the United States, and residents of the borough of Brooklyn, in the county of Kings and State of New York, have invented a new and useful Improvement in the Manufacture of Radiator-Tubes, of which the following is a specification.

10 The invention forming the subject matter hereof has already been disclosed by us in an application for Letters Patent of the United States, filed on the 13th of April, 1910, Serial No. 555,276, of which the present application is a division.

15 In our former application we have claimed, generically and specifically, the novel construction of radiator tube which our invention is designed to produce, taken as an article of manufacture, whereas in this the later application we direct our claims to the new process or method of making the same.

Our said invention relates particularly to the manufacture of cooling tubes, such as 20 are embodied in automobile radiators. In order to gain the most advantageous results with cooling apparatus of this class, it is essential, in the first place, to utilize comparatively thin sheet metal in the construction 25 of the tubes to insure rapid equalization of varying temperatures of the liquids, gases or vapors, flowing therethrough; secondly, the tubes must have a certain measure of strength, stiffness, and rigidity, to resist 30 not alone the normal internal pressure to which they may be subjected, but also the external strains that are due to the shocks, jarring, and concussions inherent in a rapidly moving vehicle; thirdly, all joints 35 should be perfectly tight; fourthly, the outline of each tube ought to coincide with the most effective position thereof; and fifthly, it is of paramount importance to provide 40 for economy of manufacture. Our invention 45 is especially designed to secure the results just noted, and, briefly stated, it consists in making a cooling tube or tubes of the above type, out of comparatively thin sheet metal having two series of differently 50 configurated angular corrugations offset relatively to one another and adapted to be brought together in parallelism to form the tube or tubes, after which the edges of the metal sheet that project beyond the corrugations are united to effect a complete

closure for each tube. The internal flow of the fluid passing through the tube is intended to traverse the series of corrugations, while the external flow of the cooling medium would be parallel to them.

60 We shall now proceed to describe in detail the several steps followed in the practice of our said method or process of manufacture, with reference to the accompanying drawing, which is hereby made a part of this specification, and in which—

Figure 1 is a plan or development of a corrugated metal sheet or blank from which a radiator tube can be made in accordance with the principle of our invention; Fig. 2 70 is a longitudinal section on the line 2—2 of Fig. 1; Fig. 3 is a side view of the blank folded up and made into a finished tube; Fig. 4 is a fragmentary perspective view of the form of tube shown in the preceding 75 view; Fig. 5 is a rear view of a pair of tubes of the same form, showing how the metal is crimped on the back during the folding operations; Fig. 6 is a sectional plan view of a group of three tubes, the sections 80 whereof, reading from left to right, are respectively taken from the lines a—a, b—b, c—c of Fig. 7, next following; Fig. 7 is a composite view of another group of three tubes, wherein the left hand tube is a section 85 on the line d—d of Fig. 6, the middle tube a section on the line e—e thereabove, and the right hand tube a full front view of the corresponding tube in the same figure; Fig. 8 is a side view of a tube of modified form, 90 also made according to our invention; Fig. 9 is a fragmentary perspective view of the modified form of tube shown in Fig. 8; Fig. 10 is a front view of a pair of tubes having 95 seams offset to one side, but also embodying the invention; Fig. 11 is a broken section view of a form of tube made up of separate sheets, by following substantially the same process or method as with the other forms previously mentioned; and Fig. 12 is a fragmentary side view of the form of tube last 100 named.

In preparing the sheet metal to manufacture one or more of the cooling tubes, the first step naturally is to cut the metal in a sheet or sheets of the required dimensions. As intimated above, while describing the figures of the drawing, a tube can be made out of a single sheet, or it may be composed of a plurality of sheets. We shall speak first 110

of its formation out of a single sheet or blank.

Taking a blank, as indicated by 15 in Fig. 1, which has been cut to size, we proceed to 5 provide it with two series of corrugations 16 and 16^a, which series are offset with relation one to the other, but are joined together by means of an intervening series of diagonal deflections 17, the latter connecting all 10 the corrugations in pairs from opposite sides of the blank. By preference, the several corrugations are made angular and pointed at both ends, as at 18. The function of the said deflections is to facilitate the folding of 15 the blank and allow the thereto appertaining corrugations to be brought into parallelism, without weakening the metal when subjected to the bending strain. In Figs. 3, 5, 6, and 8, are indicated a series of angularly 20 disposed crimps 19 which result from the diagonal deflections 17, when the corrugated sheet metal or blank 15 is centrally bent and folded over. The said crimps or chain-like folds 19 provide means for taking up the 25 surplus metal in the folding operation. Both the corrugations and deflections are conveniently produced by passing the metal sheet between rollers or dies of appropriate shape. Enough metal is left between the 30 two series of corrugations 16 and 16^a, and also at the outer ends thereof, to provide for the making of two flanges 20 and 21, presently to be described.

It is understood that the object in folding 35 the blank on a central line, transversely of the corrugated sheet, and doubling it upon itself to bring its two series of corrugations into parallelism with each other, as aforesaid, is to form a continuous passage within 40 and across the doubled sheet, such as the numeral 22 indicates in Figs. 6, 7, and 11. The passage 22, it will be observed, is circuitous and formed by placing the offset corrugations one above another so that the 45 inner angles of one series will come opposite the inner hollows of the other series, and the converse. The opposite edges of the doubled sheet are kept suitably apart and ultimately connected in a well-known manner with receptacles filled with water or other fluid the 50 flow whereof is directed transversely of the said corrugations, as before stated.

The blank having been folded in the manner above indicated, the outer ends thereof 55 are brought together and interlocked as shown by the dotted lines 23 of Fig. 2, or the full lines 24 of Fig. 6, to form a seam or joint of well known construction in the sheet metal worker's art, and as an additional precaution to secure a tight seam the joined 60 ends may be sweated or soldered together. Being firmly united one with the other, the said outer ends constitute a flange for the tube, which flange was previously referred 65 to as the flange 20, and is designed to stand

forward when the tube is set up in its allotted place in the radiator or cooling apparatus. It should be noted that while the corrugations are struck up or otherwise formed in the blank, the metal sheet is kept 70 from spreading at the ends, or else it is afterward restored to its original thickness if at all distended there at first; thus insuring to the flange a greater rigidity than is possessed by the expanded portions of the sheet. 75 Consequently, the flange 20 operates to stiffen the tube, and it presents to the air a cutting edge, which has a natural tendency to promote a free circulation thereof through the straight and open horizontal passages 80 intervening between adjacent tubes in the cooling apparatus, without in any way diminishing the normal space afforded for the circulation of water within the walls of the respective tubes. The crimps or chain folds 85 19 are preferably flattened out, as shown in Figs. 3, 6, and 8, thereby forming the aforesaid flange 21, which, like the flange 20, is of greater thickness than the combined expanded sides of the blank or metal sheet 15, 90 and similarly imparts to the tube a desirable amount of strength, stiffness, and rigidity. The flange 21 is made to stand at the rear of the tube when the latter occupies the position assigned to it in the radiator. Both 95 the said flanges 20 and 21 are straight and designed to stand in the same plane, which is normal to the closed ends of the two series of corrugations and bisects the tube centrally in the direction of its length, the plane 100 touching successively the innermost angle of each corrugation on both sides of the tube, as the line 25 in Fig. 7 clearly indicates.

The entire series of steps above described 105 as constituting our improved method or process is followed in manufacturing the tube represented by Figs. 8 and 9, the only difference that exists between the latter and the one shown in the preceding views being 110 that the ends 26 of the corrugations are beveled off or made triangular in the modified form of tube. The same is true of the construction exemplified in Fig. 10, wherein the location of the seam to one side, instead of on 115 a median line, of the tube constitutes the sole variation in the practice of the invention as hitherto explained.

In making the tube represented by Figs. 11 and 12, our invention is also applied in 120 practically all its essential particulars, only the crimping and folding of the blank are dispensed with, for the very reason that this form of tube is not made from a single blank, but rather is composed of what may 125 be termed two half-sheets of metal 15^a and 15^b, brought together by superimposition. The two half-sheets or small sheets 15^a and 15^b are corrugated like the sheet 15 within suitable distance from their ends, they are 130

superimposed so as to produce the same effect as the offsetting of the corrugations in the doubled sheet 15, their said ends being of the original thickness when united, and they 5 are joined by single seams 24^a and 24^b.

What we claim herein, and desire to secure by Letters Patent of the United States, is—

1. The herein-described method of making a radiator tube from a single sheet of metal, 10 which consists in creasing the sheet to produce therein two series of corrugations that are offset relatively to one another, forming diagonal deflections therebetween, folding the sheet to bring the corrugations into parallelism, at a proper distance one from another and seaming the ends of the sheet. 15

2. Making a radiator tube from a single sheet of metal, by forming in the metal sheet two series of corrugations offset relatively 20 to one another, with diagonal connections between the said series, and folding on a

median line to bring said corrugations into parallelism.

3. The herein-described method of making a radiator tube from sheet metal, which consists in corrugating the metal so as to leave a blank space at both ends of each corrugation, bringing two series of such corrugations horizontally together in parallelism to form a vertical passage transversely thereof, closing the tube forward and rearward, and forming either end thereof into a flange normal to the paralleling horizontal corrugations. 25 30

Signed at the borough of Manhattan, in 35 the county of New York and State of New York this 12th day of August, A. D. 1910.

EMIL BEHRINGER.
